COMPOUND LUMBER AND METHOD OF
MAKING SAMERobert H. Harwell, Lewisburg, Tenn., assignor to
Cyrus C. Houston, Lewisburg, Tenn.

Application March 5, 1930. Serial No. 433,387

5 Claims. (Cl. 20—91)

This invention relates to compound lumber and is designed for the production of relatively thin panels from small irregular lengths of wood assembled and connected in a new and improved manner such as to provide a strong and rigid panel of desired dimensions which can be conveniently handled as a unit, as for instance in lining closets and the like.

With these and other objects in view, the present invention consists in the combination and arrangement of parts as will be hereinafter more fully described, illustrated in the accompanying drawing and particularly pointed out in the appended claims, it of course being understood that changes in the form, proportion, size and minor details may be made, within the scope of the claims, without departing from the spirit or sacrificing any of the advantages of the invention.

20 In the drawing—

Figure 1 is a perspective view of a slab formed of pieces of wood assembled and connected in accordance with the present invention and preparatory to being cut into the panel of the present invention.

Figure 2 is a perspective view of a panel cut from the slab shown in Figure 1.

Figure 3 is an enlarged fragmentary sectional view taken on the line 3—3 of Figure 1 and shown partly cut or severed in the course of forming two panels from the slab.

Figure 4 is an enlarged fragmentary sectional view taken on the line 4—4 of Figure 1 and showing the joint between abutted ends of adjacent lengths or strips of wood.

Figure 5 is a similar view taken on the line 5—5 of Figure 2.

Figure 6 is a fragmentary sectional view similar to Figure 3 but showing a different form of joint between longitudinally meeting edges of adjacent strips of wood.

Figure 7 is a cross-sectional view taken transversely through the panel shown in Figure 2.

Figure 8 is a cross-sectional view similar to Figure 7 but showing a different form of joint between longitudinally meeting edges of adjacent strips of wood.

In carrying out the present invention, it is proposed to utilize short and irregular lengths of wooden strips which are ordinarily waste material and not useful because of their lack of length. For instance, in using short and irregular lengths of cedar wood for lining closets and the like, the labor necessary in handling, assembling and securing such short lengths is pro-

hibitive. According to the present invention, such short and irregular lengths of wooden strips are assembled in a plant having the necessary tools and machinery for that purpose and the pieces of wood are accurately assembled, strongly connected together and then cut and shaped so as to produce compound or composite panels of great strength and durability.

Referring to Figure 1 of the drawing, it will be seen that a plurality of strips of wood 1 of irregular lengths are assembled end to end and edge to edge to form a rectangular slab, the opposite longitudinal edges of which are defined by wooden strips 2 and 3 which extend the full length of the slabs.

As shown in Figure 4 of the drawing, the joint between the meeting ends of adjacent strips includes a tongue 4 on one strip fitting in a groove 5 in the other strip, whereby the wooden strips may be conveniently and accurately assembled with their corresponding exterior faces in proper alignment. In order to have a permanent connection between the wooden strips, the joint is provided with glue as shown at 6.

As shown in Figure 3 of the drawing, the joint between the longitudinal meeting edges of adjacent blocks or strips of wood is formed by a convex longitudinal edge 7 on one block or strip and a concave edge 8 on the other block or strip, so that these parts may be conveniently fitted together in a manner to insure the proper registering of the outer exposed faces of the blocks. Of course, glue 9 is employed to rigidly and permanently connect the blocks or strips along their longitudinal joints.

When a slab, made up as shown in Figure 1 of the drawing, has been completed, it is then placed in a suitable machine which will clamp the slab at its opposite sides so as to hold it rigidly while it is being cut by a saw in the plane of the slab so as to divide the latter into two panels of substantially half the thickness of the original slab. In Figure 3, the slab has been shown partly cut preparatory to dividing it into two panels. After the slab has been cut into panels, the opposite longitudinal edges of the panel are rabbeted as indicated at 10 in Figure 2 of the drawing, such rabbets of course being reversely disposed in order that a companion panel may have its rabbeted longitudinal edge fitted effectively to one of the rabbeted edges of an adjacent panel. By having the opposite longitudinal edges of the panel formed of continuous lengths, the intermediate short length sections are not only effectually held together but the

continuous edge portions permit of a more convenient rabbeting of the edges than could be accomplished with an edge made up of a plurality of short and irregular lengths.

5 Instead of employing the form of joint shown in Figure 3 of the drawing, a tongue and groove joint of the type shown in Figure 6 may be employed, wherein the tongue 11 is tapered somewhat so as to assist in the assemblage of adjacent strips of wood and to effect a strong and durable connection between the strips.

10 After the slab has been cut into two panels, the joint between the abutted ends of adjacent strips of course has the form shown in Figure 5 of the drawing, while the joint between the longitudinal edges of adjacent strips will have the form shown in Figure 7 of the drawing.

15 In Figure 8 of the drawing, there has been shown a panel having straight joints 12 between the longitudinal edges of adjacent strips as distinguished from the curved joint of Figures 3 and 7 and the irregular or zigzag joint shown in Figure 6.

20 It is an important feature of the present invention to first produce a slab of substantially twice the thickness of the subsequently formed panel, for the reason that strips of wood of about an inch in thickness can be conveniently handled and assembled into a slab, whereas it would be 25 very inconvenient and laborious, if not practically impossible, to first cut the short strips to their final thickness and then assemble such thin strips into the panel form. It has been found that by employing strips of about an inch thick, they can be quickly and conveniently brought together in 30 accurate alignment, glued together so as to form a slab and then the slab sawed longitudinally through its center so as to divide it into two equal panels of the desired thickness.

35 40 While, in Figure 8 of the drawing, the joints between the longitudinal edges of adjacent strips have been shown straight or at right angles to the opposite faces of the panel, it is preferred to have the joints of the form shown in Figures 3 and 6 so that any unsightly imperfections in the joint 45 will not be visible as they might be with the straight form of joint shown in Figure 8. For instance, should a hard piece of sawdust collect with the glue in the straight joint shown in Figure 8, it might space the wooden strips so as to 50 show light thru the joint and thus give a more or less unsightly appearance to the panel, all of which will be avoided by the use of the form of joint shown in Figures 3, 6 and 7, or any other 55 form of joint which is not straight or at right

angles to the front and back faces of the panel.

What is claimed is:

1. The herein described method of making compound lumber, which consists in assembling strips end for end and edge to edge and gluing the strips together into a slab whereby each face of each panel comprises the continuous faces of said strips, then severing the slab in the plane thereof and dividing it into panels of less thickness than the slab, and then longitudinally rabbeting the 80 opposite longitudinal edges of the panels. 85

2. The herein described method of making compound lumber, which consists in assembling strips of material and gluing them end for end and edge to edge to form a slab and between opposite 90 longitudinal disposed edge strips extending the full length of the slab, severing the slab and edge strips longitudinally in the plane thereof and dividing it into a plurality of panels, and then rabbeting the outer edges of the opposite longitudinal 95 full-length edge strips of the panel.

3. The herein described method of making compound lumber, which consists in assembling and gluing together strips to form a rectangular slab between longitudinal edge strips extending the 100 full length of the slab, then severing the slab and edge strips longitudinally of the plane thereof into a plurality of panels, and then rabbeting the outer edges of the continuous edge strips. 105

4. The herein described method of making compound lumber, which consists in taking a plurality of rectangular strips of irregular lengths and shaping their ends and longitudinal edges for mutual interfitting, assembling and interfitting the strips into a rectangular slab whereby each face of each panel comprises the continuous faces of said strips and gluing the joints between the interfitting parts, then severing the slab longitudinally in the plane thereof into panels, and then 110 rabbeting opposite edges of the panels. 115

5. The herein described method of making thin wooden panels for lining closets and the like from small irregular lengths of wood, which consists in assembling small irregular lengths of wood end to 120 end and edge to edge and gluing together the abutting ends and edges of said lengths of wood into a slab, whereby each face of each panel comprises the continuous faces of said lengths of wood, then severing the slab in the plane thereof and dividing it into a plurality of panels of less 125 thickness than the slab, and then longitudinally rabbeting the opposite longitudinal edges of the panels. 130
